UNITED STATES PATENT OFFICE.

HENRY G. WATROUS, OF WALLINGFORD, CONNECTICUT.

AUGER.

SPECIFICATION forming part of Letters Patent No. 606,319, dated June 28, 1898.

Application filed November 16, 1897. Serial No. 658,676. (No model.)

To all whom it may concern:

Be it known that I, HENRY G. WATROUS, of Wallingford, in New Haven county, Connecticut, have invented certain new and useful Improvements in Augers, which improvements are described in the following specification and are illustrated by the accompanying drawings.

My invention relates to that class of augers commonly called "double-twist" augers, which are formed from a flat plate twisted, and are provided with terminal cutting devices to facilitate the entrance of the tool into wood or other material in boring.

15 In general terms it is the primary object of my invention to obtain in augers of the described class the general mode of operation belonging to that other class of augers commonly called "ship-augers," which are formed on the plan of a single spiral twist or coiled bar.

As the making of a double-twist auger is much less expensive than the making of a single-twist auger, it is a particular object of the invention to render a double-twist auger 25 a good and efficient substitute for a single-twist auger in the interest of cheapness of manufacture, and as a double-twist auger is stiffer and stronger than a single-twist auger of the same size and weight it is a further 30 particular object of the invention to diminish the weight of boring-tools that have the specified general mode of operation.

It is a yet further particular object of the invention to secure uniformity of action of 35 my improved auger by definitely predetermining in a special manner the maximum thickness of the chip that is to be cut by the tool in boring.

To accomplish these objects, I adopt in the 40 construction of the auger a pod or barrel that is formed on the plan of a flat ribbon twisted, and provide that pod not with two cutters or routers after the usual manner of double-twisted augers, but with a single cutter, after 45 the manner of single-twist augers, and also with a heel which has a peculiar form and a special mode of operation.

The best mode in which I have contemplated applying the principles of the invention is 50 shown in the said drawings, by which the invention is illustrated.

In the drawings, Figures 1 and 2 are oppo-

site side views of a portion of an auger that is constructed in accordance with those principles, while Fig. 3 is a side view of the same 55 turned through an angle of ninety degrees. Fig. 4 is a front end view of the same. Fig. 5 is a front end view of my improved auger when made without a screw-point.

In the views the numerals 1 and 2 denote 60 two spiral ribs parallel and diametrically opposite to each other which wind around the axis of the auger and correspond, respectively, to the opposite edge portions of the flat plate or blank from which the implement has been 65 formed by twisting. Between them are two similar and separate spiral grooves 3 and 4, winding about the same axis from end to end of the pod in the usual manner.

The numeral 5 denotes a screw-point in advance of the spiral ribs and upon the same axis. The forward end of rib 1 is armed with a sharp side lip 6, after the manner of ship-augers, and with a router 7, whose cutting edge is continuous with a thread of the screw-point 5. When the implement is made without any screw-point, as many ship-augers are, the cutting edge of the router 7 is made longer and extends by the axis aforesaid, as shown in Fig. 5. The forward end of rib 2, instead 75 of being also armed with a cutter, ends bluntly with a heel 8, opposite the router 7. The anterior surface of this heel being beveled in two directions has two adjacent faces 9 and 80 10, which are inclined to each other at an obtuse angle. They lie on opposite sides of that part of the heel which is most advanced along the said axis of the tool and which is indicated in Fig. 4 by the broken line 11. The mutual inclination of the faces 9 and 10 necessarily varies with the pitch of the spiral ribs. In every instance it is made such as to allow the heel to circle around without impediment on the sloping bottom of the hole 85 that is being bored.

The remaining particulars of construction of my improved auger will be apparent from its mode of operation, which now remains to be described.

As above proposed, the general mode of operation of the described boring-tool is that of augers formed on the plan of a coiled bar. Like them it will bore when made without a screw-point; like them it regularly discharges

the chip through a single channel—namely, the groove 3; like them it works with the diminished friction that is due to the use of a single cutter in place of the two cutters that are 5 commonly used in other double-twist augers, and like them it definitely predetermines the thickness of the chip that may be cut independently of the attention of the workman, the inclination of the router, and the pitch of 10 the thread upon the screw-point. Unlike them it works with the diminished friction that is due to the use of two thin spiral ribs with a vacant space between them instead of a broad-backed coiled bar in contact with the 15 sides of the auger-hole; unlike them it works with the further diminished friction that is due to using a beveled heel separated from the router instead of a single cutter and heel continuously in contact with the bottom of the auger-hole; unlike them it is cheap and easy to 20 manufacture and is especially adapted by the disposition of its material to resist the torsional strains of service, and unlike them it has the superior clearance that is due to the 25 use of two discharging-channels separated only by a narrow rib. A broken chip escaping from groove 3 may be carried out by groove 4 instead of clogging behind the back of a thick coiled bar. As compared with augers that have in the head only a single spiral 30

groove, my invention has the advantage of being lighter without being effectually weaker. As compared with double-twist augers of earlier construction, it presents all the advantages of the described general mode of operation of single-twist augers, including the automatic limitation of the thickness of the chip and the consequent regularity in the action of the tool. In my improved auger these results are obtained by the novel method of 35 forming upon the blunt end of the spiral rib 2 the doubly-beveled heel 8, which slides rotarily down the sloping floor of the auger-hole as it deepens in boring.

Such being the construction and operation 40 of my invention, I claim—

In a boring-tool, the combination of two parallel ribs, coiling around a common axis, and terminally provided, one with a router and side lip, and the other with a heel, which has 45 two contiguous inclined faces, situated at a predetermined distance behind the path of the router, substantially as and for the purpose specified.

In testimony whereof I hereunto set my 50 name in the presence of two witnesses.

HENRY G. WATROUS.
